UNITED STATES PATENT OFFICE.

JOSEPH B. ESTES, OF BABYLON, NEW YORK.

INK-WELL AND OTHER RECEPTACLE.

1,277,204.

Specification of Letters Patent. Patented Aug. 27, 1918.

Application filed December 26, 1917. Serial No. 208,792.

To all whom it may concern:

Be it known that I, JOSEPH B. ESTES, a citizen of the United States, residing at Babylon, in the county of Suffolk, State of New York, have invented an Improvement in Ink-Wells and other Receptacles, of which the following is a specification.

This invention relates to an ink well although as will be understood, while I have herein shown and described the invention as particularly applicable to an ink well, it may be used as a container for mucilage, pastes, cosmetics, or other substances which it is desirable to maintain, when not in use, 10 from contact with the air so as to prevent the evaporation thereof. The object of my invention is the provision of an ink well or other receptacle, parts of which are so constructed that when placed in position they 15 form a sealed joint with one another and also to so construct the article as to provide ridges for wiping a pen, brush or other instrument in removing the contents of the receptacle therefrom, and surfaces by which 20 the portions of the contents of the receptacle, that are so wiped may drain back into the receptacle as well as to provide against the 25 contents of the receptacle becoming or tending to come into contact with the surfaces 30 which when together form the sealed joint.

This invention will be hereinafter more particularly described in conjunction with the accompanying drawings in which:

Figure 1 is an elevation of an ink well 35 made in accordance with my present invention.

Fig. 2 is a plan view of the same, and

Fig. 3 is a central longitudinal section of the same.

By reference to the drawing it will be seen that in carrying out my invention I employ a base 10, having a wall 11 extending therefrom, so as to provide for a chamber 12 for containing ink, mucilage or other 40 similar material. At an appreciable distance from the bottom of the base, which as illustrated is octagonal in plan, but which may be of any other configuration, there is a shoulder 13 and immediately above the 45 shoulder 13, that portion of the outer surface of the wall is circular and ground as indicated at 14 in order to fit with the cover as hereinafter described to form a sealed joint. 50 In the outer portion of the wall 11, above the ground portion thereof, I provide 55 a relatively deep circumferential recess

or groove placed at an inclination in the wall so as to receive any portion of the contents of the chamber 11, which might otherwise drip or run over onto the ground surface 14, preventing the proper contact between the same and the cover to make a sealed joint between these parts.

The wall 11 as illustrated, preferably terminates in an annular bead indicated at 16, 60 the upper surfaces of which are recessed as indicated at 17 and 18 providing drains for the contents of the receptacle to run back into the chamber 12 when being wiped against the ridges 19 and 20 provided for 65 this purpose in removing the contents of the receptacle by a pen, brush, or other instrument. It will be noted that the annular bead 16 also provides for a relatively deep undercut portion 21 which prevents or tends 70 to prevent the contents of the receptacle in the chamber from splashing from the same 75 in moving the receptacle.

Associated with the base and walls of the receptacle as hereinbefore described, I employ a cover indicated at 22 and which is shown as bell shaped. The inner surface of the cover 22 adjacent the edge 23 thereof is ground so as to fit the ground surface 14 of the wall 11 in order that when the cover is 80 placed in position the parts will form a sealed joint and the ground surfaces are so made that when the cover is in place the edge 85 23 of the cover is appreciably spaced from the shoulder 13 on the wall 11. The cover 90 22 may be provided with a knob or handle 24 for removing and replacing the same from and on the chamber portion of the receptacle, and as is clearly indicated in Fig. 95 3, the outer surface of the annular bead 16 at the upper end of the wall 11 is of such a diameter as to be slightly spaced from the inner surface of the cover when the parts are in position.

As hereinbefore intimated in the use of 100 the ink well or other receptacle hereinbefore described the contents of the chamber 11 may be removed by a pen, brush, or other instrument and any surplus of the contents taken on the pen or brush may be scraped therefrom against the ridges 19 and 20 formed by the inclined surfaces 17 and 18 on the annular bead 16, so that this surplus material will drain back into the chamber 12. It will furthermore be appreciated that the 105 circumferential recess 15 will receive any 110 of the contents of the chamber which may

accidentally or otherwise run over the top of the annular bead 16, and will thus be prevented from coming into contact with the ground surface 14, whereby this ground surface is maintained in the condition adapted to coact with the ground surface in the inner portion of the cover to form a sealed joint when the cover is placed in position, thereby preventing the evaporation of the contents of the receptacle irrespective of what these contents may be.

I claim as my invention:

1. A receptacle for ink and other substances comprising a base, a wall rising therefrom to provide a chamber therein and which wall terminates at its upper end in an annular bead, a portion of which overhangs the chamber in the receptacle and the upper surface of which is concaved and inclined inwardly so as to form a drain back into the chamber and provide a rib on the bead, and a cap adapted to fit over a part of the said wall.
2. A receptacle for ink and other substances comprising a base, a wall rising therefrom to provide a chamber therein and which wall terminates at its upper end in an annular bead, a portion of which overhangs the chamber in the receptacle and the upper surface of which is provided with concave recesses inclined inwardly and downwardly so as to form drains back into the chamber and provide ribs on the bead, and a cap adapted to fit over the outer surface of a part of the said wall.
3. A receptacle for ink and other substances comprising a base, a wall rising

therefrom to provide a chamber therein, and terminating at its upper end in an annular bead, a portion of which overhangs the said chamber and the upper surface of which is concaved and inclined inwardly to form a drain back into the chamber and provide a rib on the said bead, there being a circumferential recess extending into the said wall from the outer surface thereof an appreciable distance below the said bead, and a cap adapted to fit over the outer surface of the wall and to extend below the said circumferential recess therein.

4. A receptacle for ink and other substances, comprising a base, a wall rising therefrom to provide a chamber therein and terminating at its upper end in an annular bead, the upper surface of which is recessed, providing ridges for wiping an instrument employed in removing the contents of the chamber therefrom, and the inner portion of which bead extends appreciably over the sides of the chamber with an undercut recess to prevent the splashing of the contents over the surfaces of the bead, there being a circumferential recess provided in the outer surface of the wall beneath the said annular bead and extending into the wall at an inclination, and a cap adapted to extend over the upper part of the wall with a portion of the outer surface of the wall ground to receive a ground surface on an inner portion of the cap to form a sealed joint when the cap is in position on the wall.

Signed by me this 19th day of December, 1917.

JOSEPH B. ESTES.
